UNITED STATES PATENT OFFICE.

EDWARD TINKHAM GIBSON, OF BROOKLYN, NEW YORK.

BRAKE-HANDLE ARRESTER.

1,134,261.

Specification of Letters Patent. Patented Apr. 6, 1915.

Application filed December 15, 1914. Serial No. 877,343.

To all whom it may concern:

Be it known that I, EDWARD TINKHAM GIBSON, a citizen of the United States, residing at Brooklyn, in the county of Kings 5 and State of New York, have invented a new and useful Improvement in Brake-Handle Arresters, of which the following is a specification.

My invention relates to trolley car hand-brakes in which a vertically disposed brake-chain-winding shaft is provided on its upper end with a crank-arm or "brake-handle" adapted to be manually turned on a horizontal plane, and in which hand-brake 10 the said shaft is provided with a ratchet-wheel immovably secured to the shaft and adapted to be releasably engaged by a pawl to hold the shaft against revolution in a direction opposite to that in which it is 15 turned by the said brake-handle to wind upon the said shaft a brake-chain which, when wound on said shaft, operates means whereby brake-shoes are caused to bear against the wheels of the car. When the 20 pawl does not engage the ratchet-wheel a rapid unwinding of the brake-chain from the said shaft will cause the brake-handle to swing rapidly; and it not infrequently happens that a motorman operating a car 25 having this kind of brake is violently struck across his abdomen, right fore-arm, or right hand, by the brake-handle of an unexpectedly "unwinding" brake.

The object of my improvement is to provide means which will prevent accidents of the just mentioned kind from happening.

This object is accomplished by the mechanism illustrated in the accompanying drawing, in which Figure 1 represents one 40 embodiment of the invention. This Fig. 1 is a perspective view showing the application of my invention. Fig. 2 is a front elevation of the brake-handle shown in Fig. 1, and is illustrated provided with one of 45 the two coöperating parts which I provide for arresting the brake-handle, and a catch-handle. The parts *b'* and *o'* in this figure are not shown in Fig. 1 but are broken away. Fig. 3 is a top view of the parts 50 shown in Fig. 2. Fig. 4 is an end view of a vertical transverse section taken through *Y-Y* of Fig. 2. Fig. 5 is a similar section taken through *Z-Z* of Fig. 2. Fig. 6 is a similar section taken through *Z'-Z'* of 55 Fig. 2. Figs. 7 and 8 are detail views. Fig.

9 represents another embodiment of my invention.

In the drawing A represents a transverse section of the platform of a trolley car. B represents a crank-arm or "brake-handle" 60 which is secured at its proximal end to the upper end of a vertically disposed brake-chain-winding shaft C which is attached to a brake-chain D. E represents a ratchet-wheel which is carried by the said shaft and 65 which is adapted to be releasably engaged by a pawl F. In other words, the parts B, C, D, E, and F, constitute parts of the trolley car hand-brake to which I apply my invention for arresting the crank-arm or 70 brake-handle for the purpose hereinbefore set forth.

In the embodiment of my invention illustrated in Fig. 1, and made fully understandable by reference to Figs. 2, 3, 4, 5, 6, 7, and 8, G and L represent coöperating parts of a catch for arresting the brake-handle B at a predetermined point in the path that the brake-handle is caused to travel when the said shaft C is revolved. The said part G 75 is mounted to turn on a pivot-pin H which is supported in projections *i* and *i'* which extend upwardly from the horizontal plane of the top *i²* of the base-portion *i³* of a bracket I having lips (one of which lips, *i⁴* 80 is shown,) and a slot *i⁵*, and which bracket is adjustably secured by means of a bolt J to a stationary support K which latter is fastened to the framework *a* of the trolley 85 car by screws *k* and *k'*. The said part G 90 has a nose-portion *g* projecting in one direction from the said pivot-pin H and a tail-portion *g'* projecting in an approximately opposite direction from the said pivot-pin H. The said tail-portion is made heavier 95 than the said nose-portion so that gravity will tend to cause the long diameter of the said nose-portion to rest in a vertical plane, and thereby dispose the said nose-portion 100 in the position which it normally occupies and which is illustrated in Figs. 1 and 7. From this description of the pivoted-part G and the bracket I it will be seen that the said pivoted-part is free to be turned in one direction from its normal position shown in 105 Figs. 1 and 7 to the position illustrated in Fig. 8, and that a contact engagement of its tail-portion *g'* with the base-portion *i³* of the bracket I prevents its turning in an opposite direction from its said normal posi- 110

tion. The said direction in which the pivoted-part G is free to be turned is the same general one that the brake-handle B is moved in when moved forward toward the right in the act of winding the brake-chain on the shaft C. The coöperating-part L of the said catch as the latter is shown in the embodiment of my invention illustrated in Fig. 1, consists in the present instance, of a lug L having a face *l* (see Figs. 1, 7, and 8) which abuts a vertical plane, and the said lug when in its normal position projects downwardly from the horizontal plane of the undersurface of the arm-portion *b* of the brake-handle B and intersects the horizontal plane of the top of the nose-portion *g* of the pivoted-part G when the latter is in its normal position. This lug L, at its top end, is integral with the free-end portion *m* of a latch-arm M which is pivotally secured to one of the sides of the brake-handle B by a pivot-pin N on which it is adapted to turn in a vertical plane. The outer end of the said pivot-pin N is preferably supported in a bracket *b'* formed integral with the brake-handle B (see Figs. 2 and 4). The sides of the said free-end portion *m* of the latch arm M extend in vertical planes, and when the said lug L is in its normal position the said free-end portion *m* of the latch-arm loosely extends into a chamber (see O Fig. 3) having a wall *o* formed by a side surface of the arm portion *d* of the brake-handle and an opposing wall (*o'* Figs. 3 and 5) and an end wall (*o''* Figs. 3 and 5) which are integral with a bracket *b''* which is integral with the brake-handle and laterally offset therefrom. The pivoted-part G (which I have hereinbefore described) of the catch for accomplishing the object of my invention, is so positioned, with relation to the path that its coöperating-part (lug L in the embodiment of my invention shown in Fig. 1) on the brake-handle travels when the brake-handle is turned by a complete revolution of the brake-chain-winding shaft C, as to adapt the said pivoted-part G to come into a contact engagement with its said coöperating-part (L in this instance) on the brake-handle at a point in the said path and thereby stop movement of the brake-handle at this point if this just mentioned movement is the one in which the brake-handle moves when the brake-chain is unwound from the brake-chain-winding shaft C. And to accomplish the object for which I have invented my brake-handle arrester this stopping of the just mentioned movement is arranged to occur when the long diameter of the brake-handle is in a predetermined position with relation to the vertical plane of the long diameter of the trolley car. In order that the occurrence of this just mentioned stopping of the movement of the brake-handle may be prevented if the oper-

ator of the brake so desires, my brake-handle arrester is provided with a catch-handle suitably connected to one of the parts of the said catch to adapt the handle to be manually operated to move one of the parts of said catch out of its normal position for engaging the other. In the embodiment of my invention illustrated in Fig. 1, P is such a handle. This handle P has one of its ends integral with the latch-arm M, and its long diameter extends in a direction from the pivot-pin N which is substantially opposite to that in which the latch-arm M extends and is curved upwardly to a horizontal plane wherein it may be easily pressed upon by the right hand of the operator of the brake when said hand rests upon the top of the upwardly extended portion *b''* of the brake-handle.

From the description hereinbefore given of the latch-arm M, and the description just given of the catch-handle P, it will be seen that manual pressure in a downward direction upon the free-end portion *p* of the handle P will cause the lug L to rise from its normal position, and that this downward pressure may be continued till the said lug L rests, as is indicated by a dotted outline of an end view of the lug in Fig. 5, upon the horizontal plane of the undersurface of the arm-portion *b* of the brake-handle B. The said latch-arm M is made heavier than the catch-handle P so that the action of gravity will tend to restore the lug L to its normal position when downward pressure is not being exerted on the catch-handle P.

Q is a stop which is laterally offset from the brake-handle to come into contact engagement with the latch-arm M when the lug L is in its normal position.

In the embodiment of my invention shown in Fig. 9, R and S respectively represent coöperating parts of a catch for arresting the brake-handle B. The part S is an integral part of the brake-handle B itself. The part R is fixedly mounted on a horizontal rock-shaft T which has one of its ends, *t'*, journaled in a projection which extends upwardly from the horizontal plane of the top *u* of the base-portion *u'* of a bracket U which is secured by means of bolts to a stationary support V which latter is adapted to be fastened to the framework of the car. The said part R is so positioned, with relation to the path that its coöperating part S on the brake-handle travels when the brake-handle is turned by a complete revolution of the brake-chain-winding shaft (not shown in Fig. 9), as to adapt the said part R to come into a contact engagement with its said coöperating part S on the brake-handle at a point in the last mentioned path. The end *t'* of the said rock-shaft T is journaled in an upwardly projecting extension *v* of the said support V. 130

The said rock-shaft T has a downwardly projecting rock-arm t^2 which has its free end loosely pivoted to one end of a bar W which bar has its other end loosely pivoted 5 to a catch-handle X by a pivot-pin w. Said catch-handle is mounted to turn on a pivot-pin x which is supported by the said upwardly projecting extension v of the support V. The long diameter of this pivot-pin x is disposed parallel with that of the said rock-shaft T, and the said pivot-pin w is disposed at a point between the horizontal 10 plane of the axis of the pivot-pin x and that of the top of the catch-handle X. When 15 the said part R is in its normal position its nose-portion r intersects the horizontal plane of the undersurface of the brake-handle B. From the description given of the embodiment of my invention shown in 20 Fig. 9, it will be seen that the said catch-handle X is adapted to be manually operated to move the part R out of its normal position for engaging the part S, as pressure exerted against the catch-handle X in 25 the direction the arrow is pointing would cause the part R to turn on the axis of the rock-shaft T till it no longer intersects the path of its coöperating part S. In Fig. 9 the length of the bar W is exaggerated. To 30 return the catch-handle X to its normal position when manual pressure is removed from it, a suitable spring (not shown) will be employed.

Having thus described my invention, what 35 I claim as new and desire to secure by Letters Patent, is:—

1. In a trolley car hand-brake comprising a vertically disposed brake-chain-winding shaft having a crank-arm or brake-handle 40 secured to the upper end thereof and adapted to travel on a horizontal plane when said shaft is revolved the combination with said hand-brake of a brake-handle arrester having a catch and a catch-handle, said catch 45 comprising a pivoted-part having a nose-portion and mounted to turn on an axis disposed at right angles with the long diameter of said nose-portion and supported on a device secured to a suitably located immovable 50 object in the car, and a coöperating part carried by said brake-handle, said coöperating part consisting of a lug downwardly projecting from and integral with an end portion of a latch-arm pivotally secured at the 55 other end to said brake handle to turn in a vertical plane parallel with the vertical plane of the horizontal portion of the long diameter of the said brake-handle, and said lug being adapted to come into a contact engagement 60 with the said nose-portion of said pivoted-part when the two said parts are in their normal positions and the central long diameter of the said brake-handle is disposed in a predetermined position with 65 relation to the vertical plane of the central

long diameter of the car, said catch-handle having one of its ends integral with the pivoted end of the said latch-arm, and its other end disposed within easy reach of the right hand of the operator of the hand-brake when 70 said hand is on the said brake-handle and the central long diameter of the latter is disposed in the said predetermined position; and said catch-handle adapted to move the said lug out of its normal position when 75 manual pressure is exerted against it in a downward direction.

2. In a trolley car hand-brake comprising a vertically disposed brake-chain-winding shaft having a crank-arm or "brake-handle" 80 secured to the upper end thereof and adapted to travel on a horizontal plane when said shaft is revolved, the combination with said hand-brake of a brake-handle arrester having a catch and a catch-handle, said catch 85 comprising a pivoted-part having a nose-portion and mounted to turn on an axis disposed at right angles with the long diameter of said nose-portion and supported on a device secured to a suitably located immovable 90 object in the car, and a coöperating part carried by said brake-handle and adapted to come into a contact engagement with the said nose-portion of said pivoted-part when the two said parts are in their normal positions and the central long diameter of the 95 said brake-handle is disposed in a predetermined position with relation to the vertical plane of the central long diameter of the car, said catch-handle being suitably supported, and disposed within easy reach of the right hand of the operator of the hand-brake when said hand is on the said brake-handle and the central long diameter of the latter is disposed in the said predetermined 100 position; and said catch-handle being suitably connected to one of the said parts of the said catch to adapt the said catch-handle to move the part out of its normal position when manual pressure is exerted against it 105 in a predetermined direction.

3. In a trolley car hand-brake comprising a vertically disposed brake-chain-winding shaft having a crank-arm or "brake-handle" 110 secured to the upper end thereof and adapted to travel on a horizontal plane when said shaft is revolved, the combination with said hand-brake of a brake-handle arrester having a catch and a catch-handle, said catch 115 comprising a pivoted-part having a nose portion and mounted to turn on an axis disposed at right angles with the long diameter of said nose-portion, and a coöperating part adapted to come into a contact engagement 120 with the said nose-portion of said pivoted-part when the two said parts are in their normal positions and the central long diameter of the said brake-handle is disposed in a predetermined position with relation to 125 the vertical plane of the central long di-

ameter of the car; one of said parts of the said catch being carried by said brake-handle and the other being supported on a device secured to a suitably located immovable object in the car, said catch-handle being suitably supported, and disposed within easy reach of the right hand of the operator of the hand-brake when said hand is on the said brake-handle and the central long diameter of the latter is disposed in the said predetermined position; and said catch han-

dle being suitably connected to one of the said parts of the said catch to adapt the said catch-handle to move the part out of its normal position when manual pressure is 15 exerted against it in a predetermined direction.
